J. T. PARRISH,
GEAR CASING AND BAND OPERATING DEVICE FOR AUTOMOBILES.
APPLICATION FILED OCT. 20, 1919.

1,353,812.

Patented Sept. 21, 1920.

UNITED STATES PATENT OFFICE.

JOHN T. PARRISH, OF DULUTH, MINNESOTA.

GEAR-CASING AND BAND-OPERATING DEVICE FOR AUTOMOBILES.

1,353,812.

Specification of Letters Patent. Patented Sept. 21, 1920.

Application filed October 20, 1919. Serial No. 331,773.

To all whom it may concern:

Be it known that I, JOHN T. PARRISH, a citizen of the United States, residing at Duluth, in the county of St. Louis and State of Minnesota, have invented certain new and useful Improvements in Gear-Casing and Band-Operating Devices for Automobiles, of which the following is a specification, reference being had therein to the accompanying drawing.

This invention relates to an improved form of transmission band operating devices and housing thereof for Ford automobiles.

15 The principal object of the invention is to provide a more convenient and accessible mechanism of this character than heretofore employed.

Other objects and advantages of the peculiar construction will appear in the further description of the invention.

In the accompanying drawings forming part of this application and in which like reference characters indicate like parts:

25 Figure 1 is a broken top plan view of one of my improved gear housings with the band supporting and operating shafts in section.

Fig. 2 is a bottom plan view of a cover for 30 the housing.

Fig. 3 is a side elevation of one of the cover holding devices showing a portion of the cover and housing in section.

Fig. 4 is a side elevation of the assembled housing showing the pedals in elevation and a portion of the housing in section.

Fig. 5 is a transverse sectional view through the casing and centrally of one of the band supporting and controlling shafts.

40 Fig. 6 is an end elevation of one of the thrust or cam nuts carried by the shafts.

Fig. 7 comprises an elevation and section of one of the locking nuts carried by the shafts.

45 Fig. 8 is an elevation of a portion of one of the shafts upon which the locking nut is co-operatively engaged, and

Fig. 9 is a broken perspective view of the trip sleeve.

50 1 represents the lower half of a Ford transmission gear case or housing and upon which my improved upper section 2 is bolted in the ordinary manner.

The section 2 is somewhat wider than that 55 commonly used and is provided with a substantially rectangularly shaped opening or

hatch over the major portion of which is provided as a closure therefor, the cover 3. The opening in the section 2 is of a greater width than the diameter of the bands to 60 permit of same being readily removed or applied through this section while in place.

Upon one side of the section 2 is formed an enlargement 4 providing a chamber 5 for the reception of the generator commonly 65 used on such machines.

The cover 3 is provided with a rectangularly shaped groove 6 adjacent the edge of its under side, and which groove fits over the similarly shaped projection 7 about the 70 edges of the opening or hatch in the section 2.

A suitable gasket or flat packing indicated at 8 may be used within the groove 6 as desired.

75 Adjacent the upper and lower edges of the cover and pivotally carried thereby are two locking devices the handles of which are indicated at 9—9. These handles are each rigidly fixed to a stem 10 which carries upon 80 its lower end a spirally shaped locking nut 11 having an annular rib or flange 12 upon which engages an arcuately shaped channel 13 in the under side edges of the opening within the section 2. These nuts 11 are 85 formed with a portion thereof removed as indicated at 14 whereby they may be turned to such position as to permit entrance into the opening or hatch without engaging the edges thereof as clearly seen in Fig. 2 of the 90 drawings.

When the cover is applied with the nuts in this position they may be turned to locked engagement with the under side of the edges of the opening and given any degree 95 of pressure desired, for holding the cover in place, such locked position being illustrated in Figs. 3 and 4. In this manner a convenient holding device is provided for the cover and which obviates the use of bolts or nuts 100 as is evident.

The band brakes 15 and their supporting lugs 16 employed, are those commonly used on such cars but the supporting and controlling shafts are different in that they each 105 comprise a plurality of co-operative sections, and I shall proceed to describe one of such sectional shafts for the better comprehension of which attention is directed especially to Fig. 5 of the drawings.

110 17 represents that portion of the shaft upon which the pedal 18 is rigidly fixed and

extends through the side wall of the housing section 2 and to but a short distance beyond the inner wall of the housing where it is bifurcated, and is pivotally attached 5 to the reduced portion 18' of the intermediate section 19 of the shaft.

Two spirally shaped channels 20 are formed within the inner wall of the housing 10 2 about the inwardly projecting end of the shaft 17 and which inner end of the shaft is squared in cross section and carries the winged thrust nut or cam 21 which cam extends beyond the pivotal connection of the shaft section 17 with the section 19 which 15 latter is also square in cross section as at 22 adjacent its pivotal connection and carries the spacing sleeve 23, which abuts the tapered collar 24, the latter being around that portion of the shaft section 19 which is 20 rounded and may or may not rotate with the shaft as frictional contact with the lug 16 may demand.

An expansive spiral spring 25 encircles the section 19 intermediate of the band lugs 25 16 which at all times imparts a separating thrust thereto for automatically freeing the band as is common. The opposite end of the section 19 to that which has just been described is for some considerable distance 30 screw-threaded externally and has formed therein a longitudinally disposed channel 26 the extreme inner end of which is offset circumferentially as at 27 and which channel and offset is for the transmittal and reception respectively of the radially disposed lug 28 in the lock washer 29 which surrounds the shaft and carries upon the face thereof away from the lug 16 two opposed diametrically arranged V-shaped projections or teeth 30 which register with similarly shaped notches not shown, in the end of the internally screw-threaded sleeve nut 31, the end of which, opposite the lock-washer is provided with opposed rectangular recesses into which identically shaped interlocking projections on the end of the trip sleeve 32 engage when the sleeve and nut are assembled and in operative position.

The trip sleeve 32 extends within the opposite side wall of the section housing 2 to that in which the shaft section 17 is journaled and receives therein the shaft section 33 which latter has an annular collar 34 formed integral therewith and extends outwardly beyond the side of the housing and has removably attached thereto the adjusting knob 35, said knob being non-rotatably carried by the shaft section 33 and having preferably a pin connection therewith as shown at 36.

Intermediate of the collar 34 and the end of the trip sleeve 32 is an expansive spiral spring 37 which holds the sleeve in locked engagement with the nut 31 and which can

only be unlocked after the adjusting knob 65 35 is removed and the shaft section 33 forced inwardly sufficient to remove the pin 38 through the opposed elongated slots 39 within the trip sleeve provided for such purpose, said pin extending normally at 70 both ends into the slots in the sleeve while within the wall of the housing by the expansive action of the spring 37 and which forms a non-rotative connection intermediate the pin and sleeve, the necessity of which 75 will appear later.

In removing one of the brake bands all that is necessary after removing the cover 3 from the housing is to slide the trip sleeve 32 on the shaft section 33 which will compress the spring 37 and disengage the interlocked ends of the sleeve and the nut 31 when the shaft section 19 may be freely raised upon its pivotal connection with the section 17 until the band lugs 16 are wholly freed therefrom, the winged nut 21 having a slot 40 formed therein for the free upward movement of the section 19.

The object of the offset 27 in the slot 26 on the shaft section 19 will now appear, in 90 that the mechanic may slip the lock-washer 29 down within the slot until it may be turned with the lug 28 engaged in said offset and in which position the spring 25 will be slightly compressed prior to the shaft section 19 being turned completely up and at right angles to the section 17 where when such is accomplished the compressing of the spring 25 will hold the shaft section 19 with its various parts in such vertical position and out of the way for further manipulation of the brake bands.

When the assembled shaft is in position as shown in the drawings the interlocked engagement of the sleeve 32 with the adjusting nut 31 will permit of the latter being turned by the adjusting knob 35, due to the fact of the non-rotative connection formed by the pin 38 through the section 33 and extending into the slots 39 in the trip sleeve, so that all of the three brake bands may be readily adjusted from the exterior of the housing when desired.

When being assembled it is evident that the knob 35 will have to be removed from 115 the section 33 and the latter placed into its receiving hole from the interior of the housing, when the spring 37 and sleeve 32 may be put into position with the pin 38 in place when the knob 35 will be replaced from the 120 exterior of the housing and the pin 36 applied. Then the remaining portion of the shaft with the various parts which it carries are aligned as before described, the expansive action of the spring 37 normally 125 holding the trip sleeve and nut in interlocked engagement.

It will be noted that the adjacent end of

the section 19 of the shaft normally extends a short distance within the trip sleeve to insure proper alinement of the various parts.

It is well known in the art that the lugs 5 16 of the band brakes are open to permit of the free entrance and exit of the operating shaft vertically.

From the foregoing it is evident that I have produced a novel form of housing section 10 in combination with a separable band adjusting shaft which will permit of the removal or application of the band brakes with the least possible work and annoyance, and various modifications from the embodiment here shown and within the scope of the appended claims may be resorted to without departing from the spirit of the invention.

Having thus described my invention what 20 I claim and desire to secure by Letters Patent is:

1. In a power transmission mechanism of the type, wherein a plurality of bands are used to brake certain parts of said mechanism, of an upper section therefor having an opening therein greater in extent than the diameter of the transmission bands and a band adjusting shaft therein pivotally adjustable through the opening to permit 30 of the bands being removed from the housing in their entirety.

2. In a power transmission mechanism of the type wherein a plurality of bands are used to brake certain parts of said mechanism, a gear housing of the character described having an opening therein greater in transverse dimension than the diameter of the gear bands, a band adjusting shaft pivotally mounted within the housing and 40 capable of being raised pivotally through the opening, and a closure for said opening.

3. In a power transmission mechanism of the type wherein a plurality of bands are used to brake certain parts of said mechanism, the combination with a transmission gear housing of the character described having bearings in the opposite sides thereof for the transmission band shafts, of each shaft comprising a plurality of adjustable sections 45 50 the intermediate one of which is pivotally supported, substantially as and for the purpose described.

4. In a power transmission mechanism of the type wherein a plurality of bands are

used to brake certain parts of said mechanism, the combination with a transmission gear housing of the character described having an opening therein of greater width than the normal diameter of the transmission bands, of band controlling shafts journaled 60 within the housing and pivotally adjustable through the opening and means whereby the rocking of the shafts will control the bands without reciprocating the shafts.

5. In a power transmission mechanism of 65 the type wherein a plurality of bands are used to brake certain parts of said mechanism, the combination with a transmission gear housing of the character described, of shafts for controlling the transmission bands 70 each one of which comprises a plurality of alined sections the central section being pivotally adjustable for the removal or replacing of the bands and means upon the exterior of the housing for regulating the 75 throw of the operating mechanism when the shafts are rotated.

6. In a power transmission mechanism of 80 the type wherein a plurality of bands are used to brake certain parts of said mechanism, the combination with a transmission gear housing of the character described of sectional shafts for operating the transmission bands, a reciprocable thrust collar carried by each shaft within the housing and 85 means whereby when each shaft is rotated the thrust collars will be reciprocated upon the shafts and operate the ends of the bands substantially as described.

7. In a power transmission mechanism of 90 the type wherein a plurality of bands are used to brake certain parts of said mechanism, the combination with a housing for the transmission gear of an automobile having an upper opening therein of greater width 95 than the normal diameter of the transmission bands, sectional band operating shafts within the housing removable from the interior thereof, means externally of the housing for adjusting the operating shafts and 100 a closure for the opening in the housing.

In testimony whereof I hereunto affix my signature in the presence of two witnesses.

JOHN T. PARRISH.
